D. MURPHY,
SEAM COVER FASTENING FOR CAR ROOFS,
APPLICATION FILED JULY 21, 1915.

1,182,197.

Patented May 9, 1916.

UNITED STATES PATENT OFFICE.

DWIGHT MURPHY, OF PITTSBURGH, PENNSYLVANIA, ASSIGNOR TO P. H. MURPHY COMPANY, OF PARNASSUS, PENNSYLVANIA, A CORPORATION OF PENNSYLVANIA.

SEAM-COVER FASTENING FOR CAR-ROOFS.

1,182,197.

Specification of Letters Patent.

Patented May 9, 1916.

Application filed July 21, 1915. Serial No. 41,025.

To all whom it may concern:

Be it known that I, Dwight Murphy, a citizen of the United States, and a resident of the city of Pittsburgh, in the county of 5 Allegheny and State of Pennsylvania, have invented a new and useful Improvement in Seam-Cover Fastenings for Car-Roofs, of which the following is a specification.

This invention relates to outside metal 10 roofs of the type wherein the roof sheets extend crosswise of the car and are connected along their side margins by raised seams formed by strips of metal which cover the spaces between adjacent roof sheets and 15 whose edges overlap the side margins of the roof sheets.

The object of the invention is to secure the strips of metal which cover the seams between the roof sheets without puncturing 20 the roof and without the use of eaves clips or other securing means on the outside of the roof.

The invention consists in a sheet metal 25 clip which is adapted to be secured to the car under a seam cover, and over which the seam cover can be slipped endwise to embrace it and be held in position thereby.

Further objects and details of the invention appear in the following description of 30 the preferred form of the invention; and what the invention consists in is more particularly defined in the appended claims.

In the drawings, wherein the same reference characters designate like parts in the 35 several views, Figure 1 is a plan view of a portion of a car roof at the eaves, showing the end of a seam cover partly broken away to disclose the clip; Figs. 2 and 3 are cross-sections of the same on the lines 2-2 and 40 3-3, respectively; and Fig. 4 is a perspective view of a securing clip.

The car roof shown in the drawings is applied to a car having wood roof sheathing boards 11, which are supported on the car- 45 lines, and which in turn support the roof sheets 12. The roof sheets are arranged side by side with wooden battens 13 between their adjacent edges. The edges of the roof sheets are provided with up-standing flanges 14, 50 which are spaced a little away from the battens to permit slight sidewise movement of the roof sheets. The top edges 15 of the flanges 14 are turned in and slope down toward the body portion of the respective 55 roof sheets, and these sloping edges 15 termi-

nate above said body portion at about half the height of the flanges 14. The ends 16 of the roof sheets may be turned under and hooked into the rebent flanges 17 of the eaves flashing strips 18, which are secured 60 along the eaves of the car from end to end.

The seam covers 19 are inverted channel-shape, and are arranged over the battens and roof sheet flanges with their side walls 20 turned in along their bottom edges and 65 up at their extremities, forming little troughs, the inner edges 21 of which are hooked under the edges 15 of the roof sheets. The side walls 20 and inner edges 21 of the troughs are spaced from the roof sheet 70 flanges so as to permit limited sidewise movement of the roof sheets. The ends 22 of the seam covers are turned down over the ends of the battens.

The seam covers are held in position on 75 the battens by means of sheet metal clips 23, which are nailed to the battens underneath the seam covers. The clip 23 has a central groove for the batten, which is formed by pressing down wing portions 24 from the 80 sheet metal on each side of the batten into parallel planes. The side edges 25 of the clip are bent down to conform to the slope of the side walls 20 of the seam covers, and in assembled position they fit snugly within 85 the seam covers and hold them in central alinement with the battens.

The seam covers can be slipped endwise on 90 and off of the retaining clips 23. The ridge ends of the seam covers may be retained in position by the corner caps with which outside metal roofs are usually held in place. The clips 23 bear loosely upon the tops of 95 the flanges 14 and prevent the roof sheets from rising off the roof boards, while permitting them to move freely within the limits imposed by the battens 13 and the pivot bosses or other securing means usually provided at the ridge ends of the roof sheets.

The invention is not restricted to the 100 forms and arrangement of parts as shown and described.

What I claim as my invention and desire to secure by Letters Patent is:

1. A car roof comprising roof sheets movably secured upon the roof substructure, the edges of said roof sheets being spaced apart, battens between the edges of adjacent roof sheets, seam covers supported on and covering said battens and overlapping the mar- 110

gins of the adjacent roof sheets, the lower edges of the side walls of said seam covers being spaced above the roof sheets, and clips secured to said battens beneath said seam covers and projecting out from said battens over said roof sheets, the extremities of said clips engaging the inner sides of the side walls of said seam covers to retain them in centrally aligned position with respect to said

10 battens.

2. A car roof comprising roof sheets mov-
ably secured upon the roof substructure, the
edges of said roof sheets being spaced apart
and provided with up-standing flanges, bat-
15 tens between the edges of adjacent roof
sheets and spaced therefrom, seam covers
covering said battens and overlapping the
flanged margins of the adjacent roof sheets
with spaces between the side walls of said
20 seam covers and said roof sheets, and clips
secured to said battens beneath said seam
covers and projecting out from said battens
over the flanges of said roof sheets in con-
tact with their tops to hold said roof sheets

down, the extremities of said clips engaging 25
the side walls of said seam covers to retain
them in position with respect to said battens.

3. A car roof comprising roof sheets mov-
ably secured upon the roof substructure, the
edges of said roof sheets being spaced apart, 30
battens between the edges of adjacent roof
sheets, seam covers covering said battens and
overlapping the margins of the adjacent
roof sheets, and clips secured to said battens
beneath said seam covers and projecting out 35
from said battens over said roof sheets and
holding them down on the substructure, said
clips being made of sheet metal with inter-
mediate wing portions bent down on each
40 side of said battens and the extremities of
said clips engaging said seam covers to re-
tain them in position, and hold them from
sidewise movement with respect to said
battens.

Signed at New Kensington, Pennsylvania, 45
this 16th day of July, 1915.

DWIGHT MURPHY.
